United States Patent

Des. 235,288
Patented June 10, 1975

235,288

MULTIPLE SEATING UNIT

William H. Sullivan, Dallas, Tex., assignor to
The Vecta Group, Inc., Dallas, Tex.

Filed July 16, 1973, Ser. No. 379,810

Term of patent 14 years

Int. Cl. D6—01

U.S. Cl. D6—59

FIG. 1

FIG. 3

FIG. 2

FIG. 4

FIG. 1 is an end perspective view of one embodiment of the multiple seating unit;

FIG. 2 is a reduced scale perspective view of the multiple seating unit shown in FIG. 1;

FIG. 3 is an end perspective view of another embodiment of the multiple seating unit; and

FIG. 4 is a reduced scale rear view of the multiple seating unit shown in FIG. 3.

I claim:

The ornamental design for a multiple seating unit, substantially as shown.
